UNITED STATES PATENT OFFICE

129,207

DESIGN FOR A SACHET FIGURINE

Ilse Van Arlt, Chicago, Ill.

Application January 6, 1941, Serial No. 97,826

Term of patent 3½ years

To all whom it may concern:

Be it known that I, Ilse Van Arlt, a national of the German Reich, (formerly a citizen of Austria, first papers filed for United States citizenship,) residing at Chicago, in the county of Cook and State of Illinois, have invented a new, original, and ornamental Design for Sachet Figurine, of which the following is a specification, reference being had to the accompanying drawing, forming a part thereof.

I claim:

The ornamental design for a sachet figurine, as shown.

ILSE VAN ARLT.
